UNITED STATES PATENT OFFICE.

JOSEPH MILLER, OF EAST HAMPTON, NEW YORK.

MOTOR.

1,118,509.

Specification of Letters Patent.

Patented Nov. 24, 1914.

Application filed October 12, 1911. Serial No. 654,362.

To all whom it may concern:

Be it known that I, JOSEPH MILLER, a citizen of the United States, residing at East Hampton, in the county of Suffolk and State of New York, have invented certain new and useful Improvements in Motors, of which the following is a specification, reference being had therein to the accompanying drawing.

10 This invention relates to improved gas engines and more especially to that type of explosive gas engines known as four cycle engines.

15 The principal object of this invention is the production of a simple, cheap and durable gas engine which may be run at a high rate of speed with certainty and economy.

Another object of this invention is the production of an efficient gas inlet and outlet 20 control valves.

With these and other objects in view this invention consists of certain novel constructions, combinations, and arrangements of parts, as will be hereinafter more fully described and claimed.

25 In the drawings, Figure 1 is a side elevation of the engine. Fig. 2 is a vertical section thereof. Fig. 3 is a section taken on line 3—3 of Fig. 1. Fig. 4 is a section taken 30 on the line 4—4 of Fig. 2. Fig. 5 is a front view of the cam mechanism for controlling the valves.

Referring to the drawings by numerals 1 designates the crank casing which is made 35 in two sections, the upper section carrying the main cylinder 2. The inlet valve cylinder 3 is placed to one side of the main cylinder 2, and the outlet valve cylinder 4 is placed to the other side of said main cylinder 2. A water jacket 5 entirely surrounds the main cylinder and valve cylinders as clearly shown in Fig. 4, thereby forming an efficient cooling means for not only the main cylinder but also for the inlet and exhaust 45 cylinders. The inlet cylinder is provided near its outer face with an inlet opening 6 to which is connected the inlet supply pipe 7, through the medium of the bolts 8. The inlet supply pipe 7 is provided with flanges 50 9 as illustrated in Fig. 2, through which the bolts 8 pass for holding said inlet pipe in engagement with the inlet casing. The lower end of the inlet casing 3 is provided with a stuffing box 10 through which passes 55 the inlet valve control rod 11 which rod carries at its lower end a hook portion 12.

This hook portion carries at its lower end a roller 13, which roller engages the cam 14 for controlling the reciprocation of the valve control rod 11. A collar 15 is carried by the 60 rod 11 just above the hook portion 12 for limiting the upward movement of said rod. The cam 14 is provided with dished out portions 15' and an enlarged end 16 so as to give the inlet valve control rod 11 the proper reciprocating motion. Of course, the roller 13 allows the cam to act upon the lower end of the hook portion 12 with comparatively little friction. A pin 17 passes through the rod 11 and a closure nut 18 is secured to the 70 upper section of the crank casing which is illustrated in Fig. 2. A coil spring 19 is interposed between the pin 17 and the closure nut 18 for normally holding the rod 11 in its upwardly extended position.

A valve is placed within the valve casing 3 and said valve comprises an outer cylindrical shell 21 having seated upon the outer face thereof near each end a pair of packing gaskets 22 for closely fitting against the inner face of the casing 3. A plurality of radial webs 23 extend inwardly from the inner face of the shell 21 and are connected to a collar 24 into which collar is threaded the upper screw-threaded end 25 of the valve 80 operating rod 11. The upper end of the valve casing 3 is closed by means of a threaded cap 26.

The construction of the valve casing, valve and valve operating mechanism of the exhaust port is the same as that just described in connection with the inlet port. The cams 14 which operate the inlet and outlet valve control rods 11 are mounted upon shafts 27 which shafts carry upon their outer ends 95 the controlling gears 28 which gears mesh with an operating gear 29 which operating gear is in turn carried by a shaft 30. A wheel 31 is carried by the shaft 30 and to this wheel 31 is connected the rod 32. This 100 rod 32 carries at its forward end a piston 33, which piston works within the main explosion cylinder 2. The inlet valve casing 3 communicates with the explosion cylinder 2 through the medium of the inlet port 34 and the outlet or exhaust cylinder 4 105 communicates with the explosion cylinder 2 through the medium of the outlet or exhaust port 35. The usual spark plug 36 is carried by the upper end of the cylinder 2 110 for igniting the compressed charge.

The operation of the device is as fol-

lows:—The fuel is admitted into the inlet casing 3 from the pipe 7 through the port 6 and as the valve 20 is brought downwardly from the position illustrated in Fig. 5 2 the gases will pass through the valve casing and into the explosion cylinder through the port 34. At this time the valve within the exhaust casing 4 will rise so as to close the port 35, at the same time the piston 33 10 rises compressing the gases and upon the explosion of the gases the piston 33 will be driven downwardly, thereby rotating the wheel 31 and the gear 28 through the mechanism connecting said gear 28 with the 15 valve in casing 4, said valve will be drawn to the position shown in Fig. 2 to open the exhaust port 35. At the same time, the mechanism connecting gear 28 with the valve in casing 3, will cause said valve to 20 assume the position shown in Fig. 2 to close port 34. The force of the explosion will cause the piston to return to its upwardly extended position thereby forcing the burnt gases out through the exhaust casing 4 and 25 through the valve contained therein and upon its return stroke will cause the inlet valve and outlet control valve to again go through the operation just described.

From the above description it will be obvious that a simple and efficient device has been produced whereby the inlet and outlet ports will be effectually controlled so as to prevent any back firing thereby eliminating any chances of setting the carburetor on fire. It will further be obvious that an efficient means has been produced whereby the burnt gases will be readily discharged from the explosion cylinder through the medium of the piston 33 returning to its 40 upward stroke after having once been acted upon by the exploded gases. Of course, it

should be understood that the valve 20 within the casing 4 is of the same construction as the valve referred to within the casing 3 thereby allowing the gases to readily 45 pass through the valve when the position of the valve is such as to open the passageways.

What I claim is:—

An internal combustion engine comprising a cylinder provided with oppositely disposed upper fuel inlet and outlet ports, a fuel casing having a base inlet port and an upper outlet port, said upper outlet port communicating with the inlet port of the cylinder, an exhaust casing having an upper inlet port communicating with said outlet port of the cylinder and a base outlet port, a hollow valve mounted within said fuel casing for controlling the outlet port thereof and adapted to permit fuel to enter its base and discharge through the top thereof, a hollow valve in the exhaust casing controlling the inlet port thereof and adapted to permit burnt gases to enter 65 through the top and be discharged through the base thereof, said valves and said fuel casing and exhaust casing having straight walls throughout their entire length, and said valves adapted to engage said walls 70 throughout their entire stroke whereby said valves will be held against twisting movement when reciprocating within said exhaust and fuel casing, a piston in said cylinder, and means for reciprocating said piston and valves.

In testimony whereof I hereunto affix my signature in presence of two witnesses.

JOSEPH MILLER.
